(57) **CLAIM**

The ornamental design for a fan light, as shown and described.

DESCRIPTION

FIG. 1 is a bottom perspective view of a fan light showing my new design;

FIG. 2 is a top perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the fan light that form no part of the claimed design.
